UNITED STATES PATENT OFFICE.

ALMON B. LEE, OF SHELBY, MICHIGAN.

SAD-IRON.

1,182,577.

Specification of Letters Patent.

Patented May 9, 1916.

Application filed June 9, 1913. Serial No. 772,710.

To whom it may concern:

Be it known that I, ALMON B. LEE, a citizen of the United States, residing at Shelby, in the county of Oceana and State 5 of Michigan, have invented certain new and useful Improvements in Sad-Irons, of which the following is a specification.

My invention relates to improvements in said irons, and its objects are: First, to provide a means whereby gasolene may be successfully used as a constant heating element with sad irons. Second, to provide a means whereby the handle of the iron may remain permanently on the iron without danger of becoming overheated while using the iron, and, third, to provide a means whereby the gasolene will be gasified before being forced into the burner. I attain these objects by the mechanism illustrated in the accompanying drawing, in which—

Figure 1 is a longitudinal section of a sad iron on the line *x-x* of Fig. 2. Fig. 2 is an end elevation of the sad iron. Fig. 3 is a plan of the same. Fig. 4 is a plan with the 25 handle and tank and upper plate removed to show the operation of the fastening device. Fig. 5 is a transverse section of the sad iron with the handle removed and showing the relative position of the several elements that go to make up my improvements. Fig. 6 is a bottom plan of the burner, and Fig. 7 is a section of one end of the tank showing the location of the pin valve from the tank into the generator pipe.

Similar figures refer to similar parts throughout the several views.

In the accompanying drawing 1 represents the shell of the sad iron as constructed by me.

2 is the handle, and 3 represents the gasolene tank. It will be noticed that this tank lies in exact alinement with the longitudinal center of the iron and with the handle 2.

The handle 2 and the tank 3 are securely 45 attached to the upper handle supporting plate 4 and this plate is, in turn, securely connected with the center cover plate 5, and the generator pipe 7 passes from the end of the tank directly below the valve 11, to the 50 opposite end of the generator 8 to which it is securely connected so that gasolene passing from the tank through this pipe will pass into the generator and there become thoroughly gasified before passing through 55 the needle valve 9 into the burner 10, whence it is discharged through the several elongated

vents *a*, shown in Fig. 6, in position to heat the iron bottom and the generator 8. This generator is provided with a removable head 17 that may be taken off for the purpose of cleaning out the generator if it should become clogged or heavily incrusted with carbon. I avert the danger of overheating the pipe 7 by placing a deflecting plate 6 between it and the generator 8. 65

It will be noticed that with the use of the plates 6, 5 and 4 I have formed three partitions between the burner and tank with spaces between them so that the gasolene in the tank, though directly above the blazing 70 burner, is not likely to become overheated, but, in reality, will remain comparatively cool in spite of the fact that the iron itself is kept at a sufficiently high and even degree of heat to insure the perfect smoothing 75 of the articles being ironed.

I find that in order to produce the best results, and at the same time to avert the danger of overheating the handle and the tank it is necessary to turn the side edges of 80 the cover plate 4 and handle supporting plate downward, as indicated at *d-d* in Figs. 2 and 5.

It will be noted that the generator 8, the supply pipe 7, the plates 6, 5, and 4 and the 85 tank 3 are all attached to or connected with the handle 2, while the burner 10 is securely connected with the shell, 1, of the sad iron, so that when the handle is removed from the iron the parts 3, 4, 5, 6, 7 and 8 are removed with it, so that there is no possible chance for endangering the operator by reason of any leakage of gasolene, and to secure the handle and its attachments to the iron I form a hook 18 at one end of the plate 5, 90 and a latch at the other end, consisting of the lever 13 having a hand piece 12, a link *C*, the lever and link being pivotally secured to the plate 5, as at *c-c*, with the ends pivotally secured to a connecting plate or bar 16, as at 100 *b-b*, which bar is designed to be thrown into the notches *e-e* of the posts 15 15, as indicated by the dotted lines in Fig. 4 and by the solid lines in Figs. 1 and 5, so that when the lever 13 is thrown out to the position indicated by the solid lines in Fig. 4 the latches will be disconnected from the posts and the handle may be readily removed, but when the lever is carried to the position indicated by the dotted lines in this figure the links 105 will be made to engage the slots in the posts, as indicated, and the parts will be firmly 110

locked together, so that the sad iron may be used as desired.

I prefer that the tank 3 should be placed with the right hand end slightly nearer to the plate 4, or slightly out of level so as to insure the free flowage of all of the gasolene from the tank to the generator.

What I claim as new, and desire to secure by Letters Patent of the United States, is:

- 10 1. In combination, a sad iron shell, a handle, a handle supporting plate secured to the handle, a cover plate secured to the handle supporting plate, means connected with the cover plate for securing this plate and the handle to the shell, a liquid fuel tank secured in the handle parallel with the handle supporting plate, a generator located in the shell parallel with the tank, a feed pipe leading from the back end of the tank to the front end of the generator and parallel therewith, a conductor pipe leading from the back end of the generator and a needle valve thereon arranged to discharge gas into the burner.
- 15 2. In combination, a sad iron shell, a handle, a handle supporting plate, a cover plate connected therewith and forming a space between the two plates, means connected with the cover plate for detachably connecting the cover plate with the shell, a gasolene tank supported between the handle and the handle supporting plate and parallel therewith, a burner near the bottom of the shell and parallel with the tank, a generator located in the shell above and to one side of the burner and parallel there-

with, a deflector plate above the burner, a feed pipe leading from the back end of the tank into the front end of the generator, said feed pipe located between the cover plate and the deflector plate, a feed pipe leading from the back end of the generator, and a needle valve connected with said feed pipe in position to discharge gasified fuel into the back end of the burner. 45

3. In combination with the shell of a hollow sad iron, a handle secured to the top of the shell, a burner centrally located in the shell longitudinally thereof and parallel with the bottom thereof, a fuel tank 50 between the handle and the top of the shell and parallel therewith, a generator in the shell to one side of but parallel with the tank and burner, a feed pipe leading from the back end of the tank to the front end of the generator and parallel therewith, a valve in the tank for controlling the flow of fuel through the feed pipe, a feed pipe leading from the back end of the generator, a needle valve connected therewith in position to 60 discharge gas from the generator into the back end of the burner, and broad plates arranged to form several open spaces between the generator and the tank and to protect the tank and handle from the direct 65 influence of the heat generated at the burner.

Signed at Shelby Michigan May 27, 1913.
ALMON B. LEE.
